(57) **CLAIM**

The ornamental design for a joystick as shown and described.

DESCRIPTION

FIG. 1 is a front perspective view showing my new design for a joystick,

FIG. 2 is a right side view thereof,

FIG. 3 is a rear view thereof,

FIG. 4 is a left side view thereof,

FIG. 5 is a bottom view thereof; and,

FIG. 6 is a top view thereof.

The broken lines illustrate portions of the joystick that form no part of the claimed design.
